By his Attorney,
Nelson W. Bokhara

UNITED STATES PATENT OFFICE

BERNHARDT JORGENSEN, OF BEVERLY, MASSACHUSETTS, ASSIGNOR TO UNITED SHOE MACHINERY CORPORATION, OF PATERSON, NEW JERSEY, A CORPORATION OF NEW JERSEY

PULLING-OVER MACHINE

Application filed October 23, 1928. Serial No. 314,480.

This invention relates to machines for use in the manufacture of boots and shoes for pulling uppers over lasts. In some of its important aspects it relates more particularly to machines of the type illustrated in United States Letters Patent No. 1,280,613, granted on October 1, 1918, upon an application of Orrell Ashton, which include in their organization upper-pulling means, toe-embracing wipers for wiping the upper into lasted position about the toe, and devices for driving a plurality of fastenings to fasten the upper. It is to be understood, however, that in its more general aspects the invention is not limited to machines of that particular type.

An important object of the invention is to effect an improvement in respect to the positioning of fastenings driven to fasten the upper about the toe. The machine shown in the above-mentioned Letters Patent has, for each side of the forepart of the shoe, a group of tackers that are movable laterally of the shoe into upper-fastening position, and for the end of the toe another group of three tackers that are movable lengthwise of the shoe into position to fasten the upper in that location. The two outside tackers of the last-mentioned group are adjustable both lengthwise and laterally of the toe to vary the locations of the tacks in accordance with differences in the contours of the toes of shoes of different sizes and styles. It will be evident that shoes having comparatively narrow pointed toes require that these tackers be so adjusted as to position their tacks farther rearwardly with respect to the middle toe tack than shoes having comparatively square toes, so that the two outside tacks of the three driven at the end of the toe are located in closer relation to the groups of side tacks than in square-toed shoes.

In view of the above and other considerations, a feature of the present invention comprises a novel construction and arrangement affording provision for better spacing of fastenings than heretofore in operating upon shoes of different styles, through adjustment lengthwise of the shoe of the means for driving the foremost side fastenings. In the construction shown a pair of tackers

at each side located nearest to the end of the toe is thus adjustable as a unit relatively to other tackers located at the rear thereof, although the invention is not limited to that particular arrangement nor to an organization having means for driving the particular number of fastenings herein illustrated. The foremost side fastenings can thus be positioned in as close relation as desired to the end fastenings, whatever may be the position of the latter required by different styles of shoes.

In another aspect, the invention aims to effect an improvement in the control of pulling-over machines, having regard to different conditions encountered in operating upon different lines of shoes. Power-operated pulling-over machines are customarily provided with automatic means for bringing the machine to a stop at least once in the course of the cycle of operations, namely at that point in the cycle where the grippers are holding the upper under tension. In the use of machines which include means for lasting the toe, such as illustrated, for example, in the above-mentioned Letters Patent, it is considered that improved results are secured in operating upon some shoes, especially those having uppers of comparatively heavy leather, if the machine comes to a stop also at that time in the cycle when the wipers are in pressing engagement with the upper, in order to increase their molding effect on the upper. On the other hand, shoes having uppers of lighter leather do not require such a stop. The invention accordingly provides novel means which may be utilized at will to cause the machine either to come to a stop at a predetermined point in the cycle or to omit such a stop. While conditions thus especially in view are those relating to the pressing or molding effect of the overlaying means or wipers on the upper materials, it is to be understood that in its more general aspects the invention is not limited with respect to the particular point in the cycle when the stop in question occurs or is omitted.

The novel features of the invention will now be more particularly described by refer-

ence to the accompanying drawings and thereafter pointed out in the claims.

In the drawings,

Fig. 1 is a view, partly in plan and partly in section, of a portion of a machine of the type illustrated in the above-mentioned Letters Patent with the present invention embodied therein, showing the toe wipers and the several upper fastening devices or tackers in operative relation to a shoe;

Fig. 2 is a view substantially in front elevation of one of the side grippers and the associated side overlaying and fastening devices;

Fig. 3 is a view substantially in side elevation of the parts shown in Fig. 2, with some parts omitted;

Fig. 4 shows more in detail a portion of the means for supplying tacks to one of the groups of side tackers;

Fig. 5 is a vertical section of a portion of the automatic means for controlling the operation of the machine; and

Fig. 6 is a right-hand elevation, with parts in section, showing a portion of the controlling means illustrated in Fig. 5, with a portion of the mechanism in a different position of adjustment.

Since the invention is illustrated in its application to a well-known type of machine characteristic features of which are fully shown and described in various prior United States Letters Patent, including especially, the Letters Patent hereinbefore mentioned, only those portions of the machine which it is necessary to refer to particularly for an understanding of the invention are shown in the drawings and will be described in detail.

The machine is provided with a toe gripper 10, shown in dotted lines in Fig. 1, and with opposite side grippers 12 (Figs. 1 and 2) for pulling the upper over the last at the end of the toe and at the opposite sides of the forepart. It will be understood that these grippers are operated by power to pull the upper, after which the machine comes automatically to a stop with the several grippers holding the upper under tension.

Thereafter, in the further operation of the machine, the margin of the upper about the end of the toe and along the sides of the forepart is laid inwardly over a sole on the last and is fastened in overlaid position. The machine illustrated is a machine of that type having overlaying means constructed to wipe the upper into lasted position about the toe and commonly used in the manufacture of turn shoes. For this purpose, it is provided

with toe-embracing wipers comprising plates 14 of substantially the same construction as shown and described in Letters Patent No. 1,406,260, granted upon my application on February 14, 1922. These wipers are mounted to swing laterally of the shoe and are car-

ried by a front arm which is mounted for swinging movement lengthwise of the shoe in a manner characteristic of machines of the type illustrated, the lower end portion of this arm being shown in section at 16 in Fig. 1. The portion of the arm thus shown is so constructed as to serve as a tacker for driving an upper-holding tack substantially midway between the opposite sides of the end of the toe. The front arm also carries two other tackers 18 which may be termed the outside tackers of the group of three tackers thus provided for driving tacks at the end of the toe. These two tackers are so mounted on the arm as to permit either one to be adjusted independently of the other either lengthwise or laterally of the shoe. The means whereby they are thus mounted is not shown in detail, since it is of substantially the same construction as shown in Letters Patent No. 1,280,613. The position of each outside tacker 18 laterally of the shoe is determined by a screw 20 threaded therein with its inner end in engagement with the central tacker 16. For adjusting each of these tackers lengthwise of the shoe, there is provided a rod 22 pivoted at 24 to a block 26 which is secured to the tacker, this rod extending through a member 28 which is fast on the middle tacker 16 and having a nut 30 threaded on its outer end and engaging the member 28. Between the member 28 and the block 26 is a spring 32 which tends to move the tacker in one direction while the nut 30 may be utilized in opposition to this spring to move it in the opposite direction. By this means the two tackers 18 may be adjusted lengthwise of the shoe relatively to the central tacker 16 to vary the locations of the tacks in accordance with differences in the contours of the toes of shoes of different styles and sizes.

Mounted for swinging movements laterally of the shoe at the opposite sides of the forepart, as usual in machines of the type illustrated, are side arms 34, only one of which is shown in the drawings, each of these arms having mounted thereon a group of four tackers 36, 38, 40 and 42 for driving upper-fastening tacks at the rear of the toe end tacks. The tacker 36 is fast on the arm 34, while the other three tackers are mounted on a rod 44 on the arm for swinging movements laterally of the shoe to permit them to adjust themselves in accordance with the position of the toe wipers 14 at the end of the overlaping operation. To assist in controlling these swinging tackers while permitting them to move relatively to one another as described, there is fast on the arm 34 a rod 46 which extends through slots in these tackers, as shown in Fig. 1. A spring 48 mounted on a rod 50 which is fast on the tacker 36 tends to swing the tacker 38 inwardly toward the shoe as far as permitted by the rod 46 and is yieldable to permit the tacker to adjust itself as

described. The two tackers 40 and 42 are similarly controlled by opposite ends of a spring 52 on the rod 50. It will be understood that each of these side tackers, and 5 likewise each of the toe tackers hereinbefore described, includes a pair of tack fingers 54 and a tack driver 56, the several drivers of each group of tackers being operated by a driver bar on the corresponding supporting arm, substantially as shown in Letters Patent No. 1,280,613. The driver bar for operating one of the group of side tackers is shown at 58 in Fig. 2.

By reference to Figs. 1 and 3 it will be seen 15 that the tacker 38 is spaced from the relatively fixed tacker 36 by a collar 60 on the rod 44 and another collar 62 on the rod 46. These two tackers are thus permanently positioned to drive their tacks at an invariable 20 distance from each other lengthwise of the shoe. For purposes of this invention, the other two tackers 40 and 42 are mounted for rectilinear adjustment as a unit lengthwise of the shoe relatively to the tackers 36 and 38. 25 Such adjustment is effected by sliding the tackers 40 and 42 along the rods 44 and 46, these tackers being spaced apart by a collar 64 on the rod 44 and a collar 66 on the rod 46. Springs 68 and 70 mounted on the rods 44 30 and 46, respectively, tend to slide the pair of tackers 40 and 42 forwardly on these rods, and the position of these tackers with respect to such sliding movement is determined by a clamp member 72 adjustably secured to both 35 rods by means of clamping screws 74 and 76. Accordingly, when it is desired to make any adjustment of the foremost pair of side tackers, the operator loosens the clamp member 72 and positions it in a different location on the 40 rods 44 and 46, according to the adjustment desired. It will be understood that the springs 68 and 70 hold the two adjustable tackers in the positions lengthwise of the rods determined by the clamp member 72, and 45 that these springs also act to hold the tacker 38 yieldingly against the collars 60 and 62, these springs being arranged to engage suitable bearing plates in engagement with the tackers 38 and 40. It will be further understood 50 that the operative relation between the driver bar 58 and the drivers 56 of the adjustable tackers is not affected by their adjustment, since the driver bar carries a cross-rod 78 (Fig. 2) for operating these drivers and 55 along which the latter are adjustable.

The tacks are conducted to the tack fingers 54 through a slot 80 in each of the several tackers, as common heretofore. Tacks are fed to the rearmost tackers 36 and 38 of each 60 group of side tackers through tubes 82 the lower ends of which are mounted in a block 84 secured to a bracket 86 fast on a supporting bracket 87 on the side of the machine. For feeding tacks to the adjustable tackers 40 and 42 there are provided flexible tubes 88

the lower ends of which are mounted in a block 90 which is adjustable to correspond to different adjusted positions of these tackers. For the purpose of such adjustment, the block 90 is provided with a bolt 92 which extends 70 through a slot 94 in the bracket 86, this bolt having thereon a nut 96 for clamping the block 90 in adjusted position.

It will be understood that in the operation of the overlaying and tacking means, as in prior machines of the general type illustrated, the toe wipers 14 are moved lengthwise of the shoe by the front arm and are closed inwardly over the side edges of the shoe bottom by the side arms, and that after 75 the margin of the upper has been wiped inwardly by these wipers the tacks are driven by the several tackers in the relative locations determined by previous adjustments of the tackers. The machine shown is further 80 provided with means on each side arm 34 for clamping the margin of the upper against the sole at the rear of the several side tackers. This means comprises a clamp member 98 so mounted as to permit it to slide laterally of 85 the shoe and to tip heightwise of the shoe relatively to the arm 34 under control of a plate 100 and a spring 102, substantially as disclosed in Letters Patent No. 1,396,005, granted on Nov. 8, 1921 upon an invention of 90 Orrell Ashton.

The provision for adjustment of the foremost pair of each group of side tackers, as above described, is especially useful in adapting the machine to operate with most satisfactory results on shoes of different styles. As hereinbefore explained, the two outside tackers 18 of the group of toe end tackers are 100 adjustable relatively to the middle tacker 16 to position the tacks driven thereby in accordance with the contour of the end of the toe, and it will be evident that in operating on shoes having comparatively square toes, the tackers 18 must be so adjusted that the tacks driven thereby are more nearly in line with 105 the central toe tack across the end of the toe than in operating on shoes with narrow, pointed toes. It is under such conditions that the means provided by this invention for adjusting the foremost side tackers lengthwise of the shoe is especially advantageous, as serving to avoid undue spaces between the toe end tacks and the side tacks at what may be termed the corners of the toe where the curvature of the edge of the shoe bottom is pronounced and where, accordingly, there is danger that prominent wrinkles may form in the margin of the upper if the tacks are driven too far apart. It will be understood 110 that the resulting variation in the spacing between the two tacks driven by the side tackers 38 and 40 is unobjectionable, since in the locations where these spaces occur the curvature of the edge of the shoe bottom is not pro-

115
120
125
130

nounced and objectionable wrinkles are therefore unlikely to form.

In Fig. 1 the parts are shown in the positions which they occupy at that time in the cycle of the machine when the toe wipers 14 have wiped the upper inwardly over the sole and are in pressing engagement with the upper, at which time the upper-fastening tacks are driven. It is considered that in operating upon some shoes, especially shoes of that kind in which the uppers are made of comparatively heavy leather, improved results are obtained if the machine comes to a stop at the time when the wipers are thus in pressing engagement with the upper, in order to permit them to have more of a molding effect upon the upper than if they were immediately withdrawn from the shoe after the tacks are driven. On the other hand, in operating upon shoes made of lighter leather, such a stop may be unnecessary and may well be omitted for the sake of greater speed in the operation of the machine. The machine herein shown is, accordingly, provided with means which may be utilized at will to cause the machine either to come to a stop at the above-mentioned point in the cycle or to omit such a stop. This means is illustrated in detail in Figs. 5 and 6 in its relation to the type of automatic controlling mechanism characteristic of machines such as shown in the Letters Patent hereinbefore mentioned. Such automatic controlling mechanism is fully shown and described in Letters Patent No. 791,986, granted on June 6, 1905 upon an application of R. F. McFeely, and accordingly only such parts as it is necessary to refer to for an understanding of the novel means provided by this invention are herein illustrated in detail.

It will be understood that the machine is provided with a main operating cam shaft 104 driven intermittently by a pulley 106 which is controlled by a clutch (not shown), this pulley being connected to the cam shaft 104 through reduction gearing including gear wheels 108 and 110, portions of this gearing being omitted from the drawings. To stop the machine there is provided a brake shoe 112 for engaging the pulley 106, the brake shoe being fast on a vertically movable rod 114 which is connected at its lower end to the clutch, so that when the rod is moved upwardly by a spring 116 the brake is released and the clutch is set to start the machine, and when the rod is moved downwardly the clutch is released and the brake shoe applied to the pulley to stop the machine. For imparting the downward movement to the rod 114, there is fast on the cam shaft 104 a cam wheel 118 which has on its periphery three cam projections 120, 122 and 124 arranged to engage a roll 126 carried by a vertically movable member or slide 128 which is pressed upwardly by springs 130. The slide 128 has

fast thereon a lug 132 arranged to engage an abutment 134 carried by the brake shoe 112 to move the brake shoe and the rod 114 downwardly, the abutment 134 in the construction shown being adjustable by means of mechanism shown and described in Letters Patent No. 1,771,045, granted on July 22, 1930, on my co-pending application Serial No. 89,370, filed on February 19, 1926. The abutment 134 is mounted on a horizontally movable slide 136 on the brake shoe 112 which is pressed toward the left (Fig. 5) by a spring 138. To start the machine, the slide 136 is moved toward the right against the resistance of the spring 138, far enough to withdraw the abutment 134 from under the lug 132, by the action of treadle-operated mechanism not herein shown in detail but fully illustrated and described in Letters Patent No. 791,986, this mechanism including a member 140 in engagement with the left-hand end of the slide 136. It will be understood that when the abutment 134 is thus moved from under the lug 132, the spring 116 acts to raise the rod 114 with the brake shoe 112 and the parts carried thereby and thus to start the machine.

When the machine is thus started at the beginning of the cycle, the cam projection 120 is in engagement with the roll 126. Beyond this projection there is a depression 142 in the periphery of the cam wheel 118 which permits a retractive upward movement of the slide 128 in response to the action of the springs 130 far enough to permit the abutment 134 to be returned to a position under the lug 132 by the action of the spring 138. In this manner the parts are so positioned as to render the next cam projection 122 on the cam wheel effective to impart downward movement to the brake shoe 112 and the rod 114 to stop the machine when this projection arrives in position to engage the roll 126. This is the projection customarily provided in machines of the type illustrated to bring the machine to a stop at the end of the upper pulling operation while the grippers are holding the upper under tension. Thereafter the machine is again started in the same manner as before, and beyond the cam projection 122 is another depression 144 in the cam wheel which permits the parts to assume a relation such as to render the next projection 124 effective to stop the machine. This is the projection provided in the machine herein shown for the purpose of bringing the machine to a stop at the point in the cycle represented by Fig. 1 when the toe wipers 14 are in pressing engagement with the upper. It will be understood that thereafter, at the will of the operator, the machine will be again started and will complete its cycle, and that it will be brought to a stop at the end of the cycle by the cam projection 120.

In order to cause the machine to omit the stop effected, as above described, by the projection 124, there is secured in a recess in one side of the cam wheel 118 adjacent to the depression 144 therein a plate 146 having a periphery concentric with the axis of the cam wheel and formed to serve as a bridge between the two cam projections 122 and 124. To cooperate with the plate 146 there is secured to the lug 132, hereinabove described as fast on the slide 128, a bracket 148 which carries a rotatable stud 150 provided with an eccentric pin 152 on which is mounted a roll 154 for engagement with the periphery of the plate 146. The stud 150 may be turned through an angle of 180° to present the roll 154 either in position to be operatively engaged by the plate 146, as indicated in Fig. 6, or in an idle position such as to prevent the plate from acting thereon, as illustrated in Fig. 5. The stud 150 is provided with a slot in its outer end to permit it to be thus turned by the use of a screw driver, and to maintain it in either of its positions of adjustment there is provided a V-shaped pin 156 controlled by a spring 158 and arranged to enter either of two diametrically opposite recesses formed in the stud, as shown in Fig. 6. It will be evident that when the stud 150 is adjusted as shown in Fig. 6, the action of the plate 146 on the roll 154 is such as to hold the slide 128 in its depressed position during that part of the cycle corresponding to the interval between the cam projections 122 and 124. Such retractive movement of the slide 128 as to permit the abutment 134 to be returned to a position under the lug 132 can, therefore, not occur until after the projection 124 has passed the roll 154. Accordingly, the machine will continue its cycle uninterrupted from the stopping position determined by the projection 122 to the final stopping position determined by the projection 120, omitting the stop at the point represented by the projection 124. On the other hand, if it is desired to render the projection 124 effective to bring the machine to a stop at that point in the cycle, the stud 150 is turned through an angle of 180° to lower the roll 154 below the upper surface of the main roll 126, as shown in Fig. 5. With the roll 154 in this position the plate 146 has no effect on the slide 128, and consequently the main roll 126 will be received in the depression 144 of the cam wheel in response to upward movement of the slide 128, so that the abutment 134 will be returned to a position under the lug 132 in time to render the cam projection 124 effective to bring the machine to a stop by its action on the roll 126. Simple and conveniently operable means is thus provided for causing the machine to come automatically to a stop at the point in the cycle represented by Fig. 1 or to omit such a stop at the will of the operator.

In several of the appended claims the terms "tacks" and "tackers" are used for convenience of designation and not by way of limitation as to the character of the fastenings.

Having described the invention, what I claim as new and desire to secure by Letters Patent of the United States is:

1. In a machine of the class described, the combination with means for pulling an upper over a last, of upper-fastening means movable relatively to said upper-pulling means laterally of the shoe into position to drive a plurality of fastenings at each side of the forepart to fasten the upper over the bottom of the last, said fastening means comprising parts adjustable to vary the positions lengthwise of the shoe of the foremost side fastenings relatively to the positions of other side fastenings driven by said means.

2. In a machine of the class described, the combination with means for pulling an upper over a last, of upper-fastening means movable relatively to said upper-pulling means into position to drive a plurality of fastenings at each side of the forepart of the shoe to fasten the upper over the bottom of the last, said fastening means comprising at each side of the shoe parts adjustable to vary the positions lengthwise of the shoe of a pair of the fastenings located nearest to the end of the toe relatively to the positions of other fastenings driven by said means farther rearwardly in the shoe.

3. In a machine of the class described, the combination with means for pulling an upper over a last, of a plurality of tackers, each comprising a tack holder and a driver, for fastening the upper at each side of the forepart of the shoe, and a member supporting the several tackers at each side of the shoe and movable to carry them into upper-fastening positions, a pair of said tackers at each side located nearest to the end of the toe being adjustable as a unit lengthwise of the shoe relatively to said supporting member and to one or more other tackers located farther rearwardly.

4. In a machine of the class described, the combination with means for pulling an upper over a last, of two pairs of tackers at each side of the forepart of the shoe for fastening the upper, and a member supporting the two pairs of tackers at each side of the shoe and movable to carry them into upper-fastening positions, the foremost pair of tackers at each side being adjustable lengthwise of the shoe relatively to the other pair.

5. In a machine of the class described, the combination with means for pulling an upper over a last, of side arms movable laterally of the shoe and each carrying a plurality of tackers for fastening the upper over the bottom of the last, the foremost tacker on each of said arms being adjustable relatively

to the arm to vary the position of its tack lengthwise of the shoe.

6. In a machine of the class described, the combination with means for pulling an upper over a last, of means for driving a plurality of fastenings at the end of the toe and additional means for driving a plurality of fastenings at each side of the forepart to fasten the upper, said last-named means comprising parts relatively movable automatically to determine the relation between different fastenings at the same side of the shoe in respect to their positions widthwise of the shoe and relatively adjustable to vary the distance between the end fastenings and the side fastenings located nearest thereto without altering the positions of the rearmost side fastenings.
7. In a machine of the class described, the combination with means for pulling an upper over a last, of means movable lengthwise of the shoe into position to fasten the upper at the end of the toe, and additional means movable laterally of the shoe into position to drive a plurality of fastenings at each side of the forepart, said last-named means comprising parts relatively movable automatically to determine the relation between different fastenings at the same side of the shoe in respect to their positions widthwise of the shoe and relatively adjustable to vary the positions of the foremost side fastenings lengthwise of the shoe relatively to the positions of other fastenings driven by said means.

8. In a machine of the class described, the combination with means for pulling an upper over a last, of means for driving a plurality of fastenings about the end of the toe to fasten the upper including provision for adjustment prior to the upper-pulling operation to vary relatively the locations of the fastenings in accordance with the contour of the toe, and additional means for driving fastenings at the sides of the forepart comprising parts adjustable to vary the distance between the end fastenings and the side fastenings.

9. In a machine of the class described, the combination with means for pulling an upper over a last, of means for fastening the upper at the end of the toe comprising tackers relatively adjustable lengthwise and laterally of the shoe prior to the upper-pulling operation to vary the locations of tacks driven thereby in accordance with the contour of the toe, and additional means for fastening the upper at the sides of the forepart comprising tackers adjustable lengthwise of the shoe to vary the distance between the end tacks and the side tacks located nearest thereto.

10. In a machine of the class described, the combination with means for pulling an upper over a last, of a front arm and side arms movable respectively lengthwise and laterally of the shoe and each having thereon a plurality

of tackers for driving tacks to fasten the upper, a pair of said tackers located nearest to the end of the toe on each of the side arms being adjustable lengthwise of the shoe relatively to another side tacker carried by the arm at the rear of said pair of tackers.

11. In a machine of the class described, the combination with means for pulling an upper over a last, and wiper plates mounted to swing laterally of the shoe for wiping the upper into lasted position about the toe, of means for driving fastenings to fasten the upper about the end of the toe, and additional means for driving fastenings to fasten the upper at each side of the forepart, said last-named means comprising parts adjustable lengthwise of the shoe to vary the distance between the end fastenings and the foremost side fastenings.

12. In a machine of the class described, the combination with means for pulling an upper over a last, of a front arm movable lengthwise of the shoe and having thereon end-embracing wipers for wiping the upper about the toe into lasted position and also a plurality of tackers for driving tacks to fasten the upper at the end of the toe, and side arms movable laterally of the shoe and each having thereon a plurality of tackers for driving tacks to fasten the upper at the rear of the end tacks including provision for adjustment of the foremost side tackers lengthwise of the shoe relatively to the end tackers.

13. In a machine of the class described, the combination with means for pulling an upper over a last, of members movable laterally of the shoe at the opposite sides of the shoe respectively and each having thereon a plurality of devices for inserting fastenings at a side of the forepart to fasten the upper, the devices carried by each of said members being relatively movable automatically to determine the relation between different fastenings at the same side of the shoe in respect to their positions widthwise of the shoe and relatively adjustable to vary the position lengthwise of the shoe of the foremost side fastening relatively to the position of another side fastening at the same side of the shoe.

14. In a machine of the class described, the combination with means for pulling an upper over a last, of means for driving a plurality of fastenings about the end of the toe to fasten the upper comprising mechanism adjustable to vary relatively the positions of different fastenings lengthwise of the shoe, and means for driving also a plurality of fastenings at each side of the forepart comprising parts adjustable to vary the position lengthwise of the shoe of the foremost side fastening relatively to the position of another side fastening at the same side of the shoe.

15. In a machine of the class described, the combination with means for pulling an upper over a last, of a member movable length-

- wise of the shoe and having thereon means for inserting a plurality of fastenings about the end of the toe to fasten the upper comprising parts adjustable to vary relatively 5 the positions of different fastenings lengthwise of the shoe, and members movable laterally of the shoe at the opposite sides of the shoe respectively and each having thereon a plurality of devices for inserting fastenings 10 at a side of the forepart to fasten the upper, the devices on each of said side members being relatively adjustable to vary the position lengthwise of the shoe of the foremost side fastening relatively to the position of another side fastening at the same side of the shoe. 15
16. In a machine of the class described, the combination with means for pulling an upper over a last, of means for fastening the upper about the end of the toe comprising a member movable lengthwise of the shoe and having thereon a device for driving a fastening substantially midway between the sides of the toe and other devices for driving fastenings nearer the sides of the toe, said other devices being adjustable to vary the positions of their fastenings relatively to the position of the middle fastening, and additional members movable laterally of the shoe 20 at the opposite sides of the shoe respectively and each having thereon devices for driving a plurality of fastenings at a side of the forepart, said last-named devices being relatively adjustable to vary the position lengthwise 25 of the shoe of the foremost side fastening relatively to the position of another side fastening at the same side of the shoe.
17. In a machine of the class described, the combination with power-operated devices 40 arranged to act in an automatically determined cycle of operations of the machine to pull an upper over a last and to fasten the upper, of automatic controlling means adjustable at the will of the operator to cause the machine either to come to a stop at a predetermined point prior to the end of the cycle or to omit such a stop. 45
18. In a machine of the class described, the combination with power-operated instrumentalities arranged to act in an automatically determined cycle of operations of the machine to pull an upper over a last and to lay its margin inwardly over the bottom of the last and fasten it, of automatic controlling 50 means adjustable at the will of the operator to cause the machine either to come to a stop at a predetermined point in the cycle or to omit said stop. 55
19. In a machine of the class described, the combination with power-operated devices 60 arranged to act in an automatically determined cycle of operations of the machine to pull an upper over a last and to fasten the upper, of automatic controlling means comprising a cam and a member controlled by 65
- said cam for bringing the machine to a stop at a predetermined point prior to the end of the cycle, and means arranged to be positioned at the will of the operator to prevent the machine from stopping at that point in 70 the cycle. 75
20. In a machine of the class described, the combination with power-operated instrumentalities arranged to act in an automatically determined cycle of operations of the machine to pull an upper over a last and to lay its margin inwardly over the bottom of the last and fasten it, of automatic controlling means comprising a cam and a member operated by said cam to bring the machine to a stop at a predetermined point in the cycle, and means arranged to be positioned at the will of the operator to prevent the cam from thus operating said member. 80
21. In a machine of the class described, the combination with power-operated instrumentalities arranged to act in an automatically determined cycle of operations of the machine to pull an upper over a last and to lay its margin inwardly over the bottom of the last and fasten it, of automatic controlling means comprising a cam wheel having a plurality of cam projections thereon and a member arranged to be operated by the several projections in turn to stop the machine at different points in the cycle, said cam wheel having between its cam projections depressions each arranged to permit a retractive movement of said member required to render the next cam projection effective to stop the machine, and means arranged to be utilized at the will of the operator to render one of the depressions of the cam wheel ineffective and thereby to prevent the stopping of the machine by one of the cam projections. 90
22. In a machine of the class described, the combination with power-operated instrumentalities arranged to act in an automatically determined cycle of operations of the machine to pull an upper over a last and to lay its margin inwardly over the bottom of the last and fasten it, of automatic controlling means comprising a cam wheel having a plurality of cam projections thereon and a member arranged to be operated by the several projections in turn to stop the machine at different points in the cycle, said cam wheel having between its cam projections depressions each arranged to permit a retractive movement of said member required to render the next cam projection effective to stop the machine, a device carried by the cam wheel formed to serve as a bridge between two of the cam projections adjacent to the depression between said projections, and a roll on said member adjustable either into position to be controlled by said bridging device to prevent the retractive move- 100 105 110 115 120 125 130

ment of said member or into a position such as to permit said movement.

23. In a machine of the class described, the combination with power-operated devices comprising upper-pulling means and overlaying means arranged to act in an automatically determined cycle of operations of the machine to pull an upper over a last and to lay its margin inwardly over a sole on the last, of automatic controlling means adjustable at the will of the operator to cause the machine either to come to a stop with the overlaying means in pressing engagement with the upper or to omit said stop.
- 15 24. In a machine of the class described, the combination with power-operated devices comprising upper-pulling means, toe-embracing wipers and upper-fastening instrumentalities arranged to act in an automatically determined cycle of operations of the machine to pull an upper over a last, to wipe it into lasted position about the toe and to fasten it, of automatic controlling means adjustable at the will of the operator to cause the machine either to come to a stop with the wipers in holding engagement with the upper or to omit said stop.

25. In a machine of the class described, the combination with means for pulling an upper over a last, of opposite groups of tackers for fastening the upper over the bottom of the last at the sides of the forepart, and members supporting the different groups of tackers and movable relatively to the upper-pulling means to carry said tackers into upper-fastening positions, one or more of the tackers at each side located nearest to the end of the toe being mounted for rectilinear adjustment lengthwise of the shoe relatively to another tacker or tackers located farther rearwardly.

30 26. In a machine of the class described, the combination with means for pulling an upper over a last, of members movable laterally of the shoe at its opposite sides and each having thereon a plurality of tackers for fastening the upper at the forepart, and a support on each of said members on which a plurality of the tackers are mounted for relative swinging movements laterally of the shoe in operating 35 on each shoe to position the tacks in proper relation to the edge of the shoe bottom, one or more of the tackers at each side located nearest to the end of the toe being slidably adjustable along said support relatively to another tacker or tackers located farther rearwardly.

40 27. In a machine of the class described, the combination with means for pulling an upper over a last, of opposite groups of tackers for fastening the upper at the sides of the forepart of the shoe, spring means tending to move one or more of the tackers at each side located nearest to the end of the toe forwardly along the edge of the shoe bottom 45 relatively to another tacker or tackers lo-

cated farther rearwardly, and a device arranged to cooperate with said spring means to determine adjustably the location of said foremost tacker or tackers.

50 28. In a machine of the class described, the combination with means for pulling an upper over a last, of opposite side arms movable laterally of the shoe and each having thereon a plurality of tackers for fastening the upper at the forepart, a rod on each of said arms on which a plurality of the tackers are mounted for relative swinging movements laterally of the shoe in operating on each shoe to position the tacks in proper relation to the edge of the shoe bottom, spring means tending to move a pair of the tackers at each side located nearest to the end of the toe forwardly along the edge of the shoe bottom relatively to another tacker or tackers located farther rearwardly, and a device arranged to cooperate with said spring means to determine adjustably the location of said pair of tackers.

55 In testimony whereof I have signed my name to this specification.
